UNITED STATES PATENT OFFICE.

JOSEPH MUSER, OF NEW YORK, N. Y.

GUARD-RAILING.

SPECIFICATION forming part of Letters Patent No. 380,657, dated April 3, 1888.

Application filed November 28, 1887. Serial No. 256,290. (No model.)

To all whom it may concern:

Be it known that I, JOSEPH MUSER, of the city, county, and State of New York, have invented certain new and useful Improvements 5 in Guard-Railings for Trap-Doors, Hoistways, &c., of which the following is a specification.

This invention relates to an improved guard-railing for trap doors, hoistways, and similar purposes which can be folded down flush with the floor when the trap-door is closed, and which is raised and locked in raised position when the trap-door is opened, so as to prevent accidents to children and others in falling into the opening of the trap-door.

15 The invention consists of a guard-railing for trap-doors and other purposes which is set into a recess of the floor flush with the same alongside of the opening, it being composed of a stationary base-piece, a flanged top piece, 20 two sets of links pivoted, respectively, to the base-piece and intermediate connecting-pieces and to the top piece and said connecting-pieces, and a locking-lever that is pivoted to the base-piece and connected by a pivot-sleeve with one 25 of the pivot-links, so as to lift the entire guard-railing when desired, while a pivoted end section of the lever extends from one set of strips to the other set of strips, so as to lock both sets when in raised position. The folding guard- 30 railing may be made of one section extending along one end of the trap-opening, or with an extension at one or both ends, so as to extend along two or three sides of the trap-opening, as required. The folding links of the side extension 35 are connected by intermediate pieces, which are hinged to the intermediate pieces of the main section and raised and locked with the same, as will be fully described hereinafter, and finally be pointed out in the claims.

40 In the accompanying drawings, Figure 1 represents a side elevation of a section of my improved guard-railing, showing the same locked into raised position, the dotted lines showing the intermediate position of the same 45 in the act of being raised or folded. Fig. 2 shows a similar view of another section of the guard-railing. Figs. 3 and 4 are elevations showing the sections of the guard-railing folded up. Fig. 5 is a top view of Fig. 3. Fig. 6 is 50 a detail top view, partly in horizontal section, showing the locking device of the guard-railing; and Fig. 7 is a plan showing the location

of my improved guard-railing along two sides of a trap-opening.

Similar letters of reference indicate corresponding parts.

Referring to the drawings, A represents the angular base-piece of my improved guard-railing for trap-doors and other purposes; B, the angular top piece of the same; C C, the lower set of pivot-links; C' C', the upper set of pivot-links, and D D the transverse connecting-straps of the pivot-links C C'. The lower links, C C, are pivoted to the base-piece A and the connecting-straps D, and the upper links, 65 C', are pivoted to the connecting-straps D and the top piece, B. One connecting-strap D is pivoted to a group of pivot-links, C C', at one side of the center line of the section, while the other strap D is pivoted to the group of 70 links C C' at the other side of the center line. When the guard-railing is to extend along two sides of the trap-door opening, the base and top pieces, A and B, are extended at one end at right angles in the form of an L. In this 75 case side links, C C', are used, which are pivoted to the extensions A' B' of the base and top pieces, said side links being connected by a hinged strap, D', to the next adjoining intermediate connecting-piece D. The hinged side 80 strap, D', is formed of two pieces, d d', the longer piece, d, of which is pivoted to the side links, C C', as shown in Fig. 2, while the shorter piece, d', is hinged to the piece d and to the strap D', as shown in Figs. 2, 4, and 5. 85

The right-hand group of pivot-links C C' of the main section of the railing is slightly bent at the upper and lower ends, or pivoted at a greater distance from the angular base and top pieces, so as to permit the folding of the left-hand group of pivot-links back of the right-hand group when the guard-railing is to be folded up. The raising and locking of the entire guard-railing is accomplished by a lifting and locking lever, E E', which is pivoted to a 95 stationary lug, e, of the base-piece A, the section E of the lever being connected by a pivot-sleeve, e', to one of the lower pivot-links, C, of one group of links, while the section E' of the lever is pivoted to the outer end of the section 100 E and provided with a keeper, e'', a recess, e'', and a knob or button, e''. The keeper e'' engages one of the pivot-links C' of the other group of links, while the recess e'' engages a

pin, e^5 , of one of the lower pivot-links, C, so as to lock thereby, by the joint action of the sleeve e' , keeper e^2 , section E', and pin e^5 , both groups of links firmly in raised position. For 5 lowering the guard-railing the lever-section E' is released from the pin e^5 , the keeper e^2 released from the upper link, C', while the lever-section E moves by its pivot-sleeve e' along the pivot-link C of the left-hand group, whereby 10 the pivot-links of one group pass back of the pivot-links of the other group, as shown in dotted lines in Figs. 1 and 2, until finally all the pivot-links are folded together and the top piece, B, arrives in position on the base-piece 15 A, as shown in Figs. 3 and 4. During the folding action of the guard-railing the group of links of the side section or extension is also folded up, while the hinged sections d d' of the side strap, D', are drawn by their connecting-strap D into line with the folded 20 groups of the main section, as shown in Figs. 3 and 5. In the folded position the entire guard-railing is flush with the floor. When the trap-door is opened and the guard-railing 25 is to be raised, so as to prevent accidents by falling into the trap-door opening, the lever E' is lifted by taking hold of its knob e^4 , so that its pivot-sleeve e' raises the groups of links C C' and C² C³ and the connecting-straps D D', 30 of which the hinge-strap D' moves back into the plane of the group of side links, as shown in Fig. 2. When the main and side sections of the guard-railing are raised to their full 35 height, the pivoted lever-section E' is moved sidewise, so as to engage by its keeper e^2 and recess e^3 the pin e^5 and the group of pivot-links, as before described. The entire guard-railing is thus firmly locked, so as to furnish a reliable 40 means for preventing accidents to grown people and children in connection with the openings of trap-doors, hoistways, and the like.

Having thus described my invention, I claim as new and desire to secure by Letters Patent—

1. A guard-railing for trap-doors and other 45 purposes, composed of a base-piece, a top piece, a set of lower pivot-links, a set of upper pivot-

links, intermediate transverse straps which connect the sets of pivot-links into groups, and a lifting and locking lever provided with a pivot-sleeve connected to the links of one 50 group, and with a locking device for connection with the other group, substantially as set forth.

2. The combination of a base-piece, a top piece, sets of folding links pivoted, respectively, to the base and top pieces, intermediate connecting-strips pivoted to the sets of pivot-links so as to form groups, and a lifting and locking lever pivoted to the base-piece and made of two pivoted sections, one section being provided with a pivot-sleeve that moves along one of the pivot-links of one group, while the second section is provided with locking devices for interlocking with one of the pivot-links of the other group, substantially 65 as set forth.

3. The combination of a base-piece, A, having an extension, A', a top piece, B, having a similar extension, B', a lower set of pivot-links, C, an upper set of pivot-links, C', side links, C² 70 C³, transverse connecting-straps D D' D', connecting the pivot-links so as to form groups of links, the side strap, D', being formed of two sections hinged together and to one of the straps D, and a lifting and locking lever formed 75 of two pivoted sections, E E', of which one section is pivoted to the base-piece A and provided with a pivot-sleeve, e' , engaging one of the pivot-links of one group of links, while the second section is provided with locking 80 devices for engaging the pivot-links of the upper group of links, so as to lock the parts of the guard-railing in raised position, substantially as set forth.

In testimony that I claim the foregoing as my 85 invention I have signed my name in presence of two subscribing witnesses.

JOSEPH MUSER.
